UNITED STATES PATENT OFFICE.

ARTHUR E. HAYWARD, OF SWINDON, ENGLAND.

BRAKE SLACK ADJUSTER FOR RAILWAY VEHICLES.

Application filed May 2, 1921. Serial No. 466,124.

(GRANTED UNDER THE PROVISIONS OF THE ACT OF MARCH 3, 1921, 41 STAT. L., 1313.)

To all whom it may concern:

Be it known that I, ARTHUR EDWARD HAYWARD, a subject of the King of Great Britain, residing in Swindon, England, have invented certain new and useful Improvements in Brake Slack Adjusters for Railway Vehicles (for which I have obtained patents in Great Britain, No. 105,- 629, dated April 25, 1916, and in India, No. 10 4359 of 1919, dated April 14, 1919), of which the following is a specification.

This invention relates to brake slack adjusters for railway vehicles in which the brake rigging is so arranged that, when the 15 brake is released after being applied, the blocks are automatically withdrawn from rubbing contact with the wheels.

It has before been proposed to form on one or two members a plurality of indentations and for a pawl pivoted to a member 20 to seat itself in one of the indentations to apply the brake while a second pivoted pawl was adapted to gather the slack as required.

25 I am aware that it has also been proposed for the indentations to be on one member and for one pawl on another member to seat itself in one of the indentations to apply the brake and to skip an indentation when slack has to be gathered on the release of the brake.

The object of the invention is an improved method of slack gathering which enables the second set of indentations and the 30 second set of pawls to be dispensed with.

The invention comprises a particular method of slack gathering, wherein an element is pivoted to a member of the rigging and moves in a vertical plane, while the 40 indentations are in a plane inclined to the radius line so that when the free end of a limb of the rigging seated in either of the indentations (except the last) fails, on the release of the brake, to synchronize with 45 the same indentation (by the length of a tooth) the element drops and the limb is reseated in a fresh indentation.

The element can be so arranged that a 50 straight slot therein would be at an angle to the horizontal, the indentations being formed on the upper side of the slot.

In a modified form the length of the radius line would be considerably reduced necessitating that the plane of the indentations be on a curve which would be eccen-

tric to its pivot to give the necessary distance apart to gather a more or less equal amount of slack each time the limb is reseated in a fresh indentation. The centre of the circle, of which the curved surface 60 on which the indentations are formed is on a line drawn at right angles to a line at an angle to the radius line from the pivot of the element.

The depth of the indentations is such that 65 when the slack has been gathered, the blocks, on release of the brake, can slack sufficiently to be clear of rubbing contact with the wheels.

A spring, which may be of the coiled 70 type, can be used, one end of which would be connected to some part of the vehicle while the other end would be connected to the member to which the element is pivoted or to the element itself to exert a pull and 75 keep it in the "off" position.

The accompanying drawings exemplify the invention, Figure 1 being a side elevation of the invention applied to a known type of brake rigging in which the power 80 for the application of the brake is a hand lever. Figure 2 is a side elevation and Figure 3 a plan on an enlarged scale of the brake slack gathering member and the power rod.

Figure 4 is a side elevation of a modified form of the invention shewing the power rod supported.

The usual brake mechanism is represented by the brake shaft *a* working in suitable bearings *b*¹ formed in hangers *b*, fixed to the frame *c* of the vehicle, *a*¹ and *a*² arms formed with or attached to the brake shaft *a*, *a*³ is a lever arm also attached to or formed with the brake shaft *a*, *d* and *d*¹ 90 are pull rods, one end of each of which is connected respectively to the arms *a*¹ and *a*² of the brake shaft while the other ends are connected to the brake block hangers or mechanism (not shewn in the drawings), *e* 100 is a power rod connected by means of an eye *e*¹ to the forked end of an arm *f*¹, secured to or formed in one with a tumbler shaft *f* while the other end is forked and connected to the brake gathering member 105 *m*. The tumbler shaft *f* has its bearing in a hanging bracket *g* fixed to the frame *c* of the vehicle. The brake is applied by a hand lever *j* and is automatically returned to its normal position on the reverse movement 110

of the said hand lever by a spring connected to some part of the brake rigging and shown at o . The power rod e is forked and the two parts e^2 of the fork are connected to the brake slack gathering member m by means of pins m^1 . The gathering member m is in the form of two plates, one on each side of the forks, while the opposite side is connected to one end o^1 of the 10 coiled spring o , the other end o^2 of the latter being connected to the eye of a rod p . The rod p is secured by adjustable means p^1 to a bracket r secured to the framing c of the vehicle. The slack gathering member 15 m has a slot through each of the plates, and in alignment with each other, the slots being inclined and leaning towards the direction of the pull, one side of each of the slots having a plurality of teeth m^2 and the opposite sides m^3 plain. The pin a^4 passing through the lever arm a^5 when the 20 brake blocks are new, seats itself in the bottom recess of one of the teeth m^2 .

The length from the top m^4 of the teeth 25 to the base m^5 thereof of the brake slack gathering member should be such as to permit the brake rigging, when the slack has been taken up, to slack back in order that the brake blocks may be released from rubbing contact with the wheels of the vehicle.

One end o^1 of the coiled spring o is attached to an eye m^6 on the slack gathering member.

In a modified form of the invention as 30 shewn in Figure 4 the pull rod r^2 is shortened, one end being connected to the brake slack gathering member t by means of a pin t^1 ; the member is as before described in the form of two plates one on each side of the 35 eye on the end of the pull rod, while means such as a rivet t^3 prevent the plates from getting out of alignment with each other. The slack gathering member t has a slot through each of the plates, and in 40 alignment with each other, the slots lying on a curve eccentric to its fulcrum as before described and leaning towards the direction of the pull, one side of the slots having a plurality of teeth t^2 and the opposite 45 sides t^4 plain. The pin a^4 passing through the end of the lever arm when the brake blocks are new, seats itself in the bottom recess of one of the teeth t^2 . The end of the 50 rod r^2 in this arrangement has to be supported on a support s , means such as a roller s^1 being provided to relieve the fric-

tion of the rod when moved in the application or the release of the brake.

The coiled spring o is attached to a projection r^1 on the rod r^2 in order that when the pivoting pawl l is released the slack gathering member can be returned automatically to its normal or "off" position.

Having thus described the nature of the said invention and the best means I know of carrying the same into practical effect I claim:—

1. A brake adjusting apparatus for railway vehicles, comprising a power rod, a plate secured to said power rod having a slot inclined to the longitudinal axis of said power rod, said slot having teeth formed on one side thereof, a pivoted lever, a pin on said lever engaging with the teeth of said slot, a pull rod pivotally connected to said pivoted lever and means for restoring said slotted plate to normal. 70

2. A brake adjusting apparatus for railway vehicles, comprising a power rod, a plate secured to said power rod having a slot inclined to the longitudinal axis of said power rod in the direction of the force exerted by said rod, said slot having teeth formed on one side thereof, the opposite side of the slot being plain, a pivoted lever, a pin on said lever engaging with the teeth of said slot, a pull rod pivotally connected to said pivoted lever and means for restoring said slotted plate to normal. 80

3. A brake adjusting apparatus for railway vehicles, comprising a power rod forked at one end, two plates, one on each side of said forked ends, each of said plates having an inclined slot, one side of each slot being toothed, a pivoted lever, a pin on said lever engaging with the teeth of said slots, a pull rod pivotally connected to said pivoted lever and means for restoring said slotted plate to normal. 95

4. A brake adjusting apparatus for railway vehicles, comprising a power rod forked at one end, two plates, one on each side of said forked ends, each of said plates having an inclined slot, one side of each slot being toothed, a pivoted lever, a pin on said lever engaging with the teeth of said slots, a pull rod, and spring means tending to move to said slotted plates in opposition to the power rod. 100

In testimony whereof I have signed my name to this specification.

ARTHUR E. HAYWARD.
